[57] CLAIM

The ornamental design for a thread organizer, substantially as shown and described.

DESCRIPTION

FIG. 1 is a perspective view of a thread organizer showing my new design;

FIG. 2 is a front elevational view, the rear view being a mirror image thereof;

FIG. 3 is a right side elevational view thereof;

FIG. 4 is a left side elevational view thereof;

FIG. 5 is a top plan view thereof; and

FIG. 6 is a bottom plan view thereof.
